UNITED STATES PATENT OFFICE.

WALTER L. CURTIS, OF WORCESTER, MASSACHUSETTS.

ROLLER OR WHEEL.

No. 884,720.

Specification of Letters Patent.

Patented April 14, 1908.

Application filed January 3, 1908. Serial No. 409,171.

To all whom it may concern:

Be it known that I, WALTER L. CURTIS, a citizen of the United States, residing at Worcester, in the county of Worcester and 5 State of Massachusetts, have invented a new and useful Roller or Wheel, of which the following is a specification.

The object of this invention is to provide a new and improved roller or wheel especially 10 adapted for use in roller skates, casters, and similar locations where a strong, light article is needed, which can be made of sheet metal and so constructed as to be made practically in one integral piece, whereby the same will 15 not come to pieces from wear and jar.

The invention is illustrated in the accompanying drawing, referring to which

Figure 1 is a side elevation of the improved construction. Fig. 2 is a central sectional 20 elevation, and Figs. 3 and 4 are views similar to Fig. 2 illustrating modifications.

Referring to the drawings and in detail, the improved wheel or roller will be seen to be made and constructed as follows: 25 10 designates a circular rim or tread made out of sheet metal. The sheet metal is doubled back at each edge or side under the rim as at 11—11, so that the rim or tread in substance will be double. From the in-bent 30 portions 11—11 the sheet metal extends centrally to form flanges 12—12. If desired these flanges may be bored or punched out as at 120, so that the flanges 12—12 will form spokes. From the flanges 12—12 the 35 sheet metal extends outwardly as at 13—13 to form a double central hub. A wheel or roller constructed in this way is very strong and efficient. It is provided with a long wearing tread, and being formed from sheet 40 metal will not jar loose or come to pieces from wear or blows.

15 designates a double ball-rest which is made out of one piece or cylinder of sheet metal, and which has a central inner bend or 45 depression 16 so that a double ball-way or rest is provided. This ball-way or rest is held in place in the double central hub by turning or bending the ends or edges of the central hub down over the edges or ends of 50 the double ball-rest, as at 14—14. In this way the double ball-rest is tightly and securely held in place in the wheel or roller.

In Fig. 3 a similar construction is shown, except that the ball-rest 17 therein employed 55 has a single central groove 170 for a single set of balls.

By reference to Figs. 2 and 3 it will be seen that the outer edges of the hub project over the outer edges of the ball-rest but do not quite cover them so that an annular ledge 19 60 is provided for receiving and holding the dust cap (not shown).

In Fig. 4 a modification is shown in which two ball rests 18—18 having flanges 180 are pressed or forced securely into the double central hub 130—130 of the wheel or roller. 65

By the aforesaid construction an admirable wheel or roller is provided which is especially adapted for use in the locations specified.

The details herein shown and described may be greatly varied by a skilled mechanic without departing from the scope of my invention as expressed in the claims.

Having thus fully described my invention, 75 what I claim and desire to secure by Letters-Patent is:—

1. A wheel having a two-part central hub, double flanges or spokes, and a double rim or tread all formed from one piece of metal, 80 each edge of the tread being integrally connected with one of the flanges whereby pressure imparted to either outer edge of the tread will be transmitted to both flanges.

2. A wheel having an annular one-piece 85 double ball rest having an annular central depression.

3. A wheel having a two-part central hub, flanges or spokes, and a rim or tread, all formed of one piece of metal, and a ball-rest 90 held in place in said two-part central hub by inwardly turned flanges on the edges of said hub.

4. A wheel having a two-part central hub, flanges or spokes, and a double rim or tread, 95 all formed from one piece of metal, and a double ball-rest formed of one piece and having a center inwardly projecting, said ball-rest being held in place in said two-part central hub by flanges inwardly turned on the 100 edges of said hub.

5. A wheel having a two-part central hub, flanges or spokes, and a rim or tread formed of sheet metal, and a ball-rest, the outer annular edges of the hub projecting over upon 105 the outer faces of the ball-rest all around to form therewith an annular ledge outside of the ball-rest for receiving a dust cap.

6. A wheel having a two-part central hub, flanges or spokes, and a rim or tread all 110 formed from one piece of metal, the outer annular edges of the hub projecting inwardly

all around, and a ball-rest held between said inwardly projecting edges.

7. A wheel having an annular double ball-rest provided with a central annular depression and formed of one piece of sheet metal of substantially uniform thickness.

In testimony whereof I have hereunto set

my hand, in the presence of two subscribing witnesses.

WALTER L. CURTIS.
